UNITED STATES PATENT OFFICE.

ALBERT H. MERRILL, OF OCEAN SPRINGS, MISSISSIPPI.

BAND-STAMP.

No. 911,424.

Specification of Letters Patent.

Patented Feb. 2, 1909.

Application filed August 19, 1908. Serial No. 449,222.

To all whom it may concern:

Be it known that I, ALBERT H. MERRILL, a citizen of the United States, and a resident of Ocean Springs, in the county of Jackson 5 and State of Mississippi, have invented certain new and useful Improvements in Band- Stamps, of which the following is a specification.

My invention is an improvement in band 10 stamps, and consists in certain novel constructions and combinations of parts herein- after described and claimed.

Referring to the drawings forming a part 15 hereof Figure 1 is a side view of a stamp constructed in accordance with my improvement. Fig. 2 is a section on the line 2—2 of Fig. 1. Fig. 3 is an enlarged detail view of the ratchet wheel and pawl, and Fig. 4 is a detail perspective view of one of the type 20 holders.

The present embodiment of my invention comprises a frame consisting of a top 1, and side members 2, between which is journaled 25 spaced shafts 3 and 4, and the frame is provided with a handle 5 for convenience in manipulating the same. Upon each of the shafts 3 and 4 is secured a roller, 6, 7, the roller 6 being of greater diameter than the roller 7 as shown in Fig. 2.

30 An endless belt 8 is mounted on the rollers, and the said belt is provided with a plurality of type holders 9, to be presently described in detail, and the said large roller 6 is provided at one end with a ratchet 35 wheel 10, normally engaged by the pawl 11, on a vertical sliding bar 12 mounted for engagement in the frame.

The bar 12 is provided with a head 13, and a spring 14 is arranged between the head 40 and the top 1, of the frame. It will be observed that the side members 2 of the frame are somewhat smaller at their outer end than at their inner, in accordance with the shape of the endless carrier on the rollers.

45 The type holders comprise each a base 15, having its ends extended as at 16 and provided with openings 17 whereby it may be secured to the belt or carrier, and side members 18, 19 connected at one end as at 50 20, but disconnected at the other. The side member 19 near its top is bent inwardly as at 22, and again parallel with the side mem- ber 18 as clearly shown in Fig. 4. The types 23 are rubber, and are adapted to be

introduced between the side members 18, 19 55 from the open end, each of the types being provided with an offset side to fit the side member 19 whereby they may be retained in place.

The stamp is especially adapted for use in 60 entering lists of names on either books or papers, or both, as for instance pay rolls. The usual system is to copy in the pay roll book, either weekly or monthly, the names of every one working the previous week in 65 pen and ink. This work has then to be duplicated on the pay rolls, and again repeated on the pay envelops.

In the present device a stamp is provided 70 for each name and it is evident that the impression from each individual stamp may be repeated as many times as desired. In case the name of an employee is no longer used for any reason, it may be removed from the belt and another substituted therefor. 75

After an impression is made, by depressing the sliding bar 12, the upper roller is rotated to bring a new stamp into position, and in practical use, the ratchet wheel would be provided with a tooth corresponding to each 80 stamp.

In ordinary use, a plurality of interchangeable type carrier belts are made use of, so that when all the names on one belt have been stamped, others may be substituted by simply removing the shafts 3 and 4 (Fig. 2) and placing the new belt over the rollers 6 and 7. The shafts are made removable for this purpose. It will be understood 85 that the type holders and types may be 90 made in any other suitable form, it only being necessary to provide a holder which will hold the types in their proper position.

I claim:

In a device of the class described, a han- 95 dled frame, a pair of spaced rollers journaled in the frame, one of said rollers having integral therewith a ratchet wheel, an endless belt supported on the rollers, a plurality of type holders arranged transversely of the belt, and in spaced and parallel relation, and a spring-supported slidable pawl engaging the ratchet wheel for moving the belt where- by to bring the stamps into proper position. 100

ALBERT H. MERRILL.
